CLAIM

The ornamental design for a flexible pouch, as shown and described.

DESCRIPTION

FIG. 1 is a perspective view of a flexible pouch showing my new design;

FIG. 2 is a front elevational view thereof;

FIG. 3 is a side elevational view thereof;

FIG. 4 is a top plan view thereof;

FIG. 5 is a bottom plan view thereof;

FIG. 6 is a back elevational view thereof; and,

FIG. 7 is the opposite side elevational view thereof.

It should be appreciated that the broken lines are merely illustrative of the environment of the design, and not part of the claimed design.
